[57] CLAIM

The ornamental design for a combined seat and partition unit, as shown and described.

DESCRIPTION

FIG. 1 is a front perspective view of a combined seat and partition unit showing a first embodiment of my design.

FIG. 2 is a top plan view of the first embodiment.

FIG. 3 is a front elevation of the first embodiment.

FIG. 4 is a left side elevation of the first embodiment of the invention.

FIG. 5 is a right side elevation of the first embodiment.

FIG. 6 is a rear elevation of the first embodiment.

FIG. 7 is a front perspective view of a second embodiment of the combined seat and partition unit shown in FIG. 1.

FIG.1
